UNITED STATES PATENT OFFICE.

ALBIN H. HUTCHINGS, OF BUFFALO, NEW YORK.

SASH-FASTENER.

1,299,834.

Specification of Letters Patent. Patented Apr. 8, 1919.

Application filed June 22, 1917. Serial No. 176,440.

To all whom it may concern:

Be it known that I, ALBIN H. HUTCHINGS, a citizen of the United States, residing at Buffalo, in the county of Erie and State of 5 New York, have invented new and useful Improvements in Sash-Fasteners, of which the following is a specification.

This invention relates to a sash fastener, and has for its object the production of a device of this character which is simple and inexpensive in construction, easily operable, and also capable of being readily applied to practically all windows as now generally constructed.

15 In the accompanying drawings:

Figure 1 is fragmentary elevation of a window, showing my improved sash fastener applied to the opposing parts of its upper and lower sashes. Fig. 2 is a fragmentary 20 vertical section, on an enlarged scale, taken on line 2—2, Fig. 1. Fig. 3 is a rear end elevation of the sash fastener applied to the lower sash. Fig. 4 is a top plan view of the same. Figs. 5 and 6 are detached 25 perspective views of the slide and base of the sash fastener. Fig. 7 is a top plan view of the blank from which the base of the fastener is constructed.

Similar characters of reference indicate 30 corresponding parts throughout the several views.

Although this invention is applicable to windows of various kinds and also other forms of closures for openings, the same is 35 shown in the drawings, for example, applied to a window having a frame 1, a lower inner sash 2 and an upper outer sash 3, these sashes being guided at the corresponding vertical edges on the frame in the usual and 40 well known manner.

In its general organization, my improved sash fastener which is associated with these two sashes, comprises a base mounted on the lower sash, a slide or carriage mounted on 45 the base so as to be capable of movement toward and from the inner face on the side of the upper sash, and a pair of inclined gripping members pivotally mounted on the slide and adapted to engage the inner side of the 50 upper sash.

The base may be variously constructed, but in its preferred form the same is constructed of sheet metal and comprises a bottom plate 4, two longitudinal guideways 5 arranged on the front parts of the opposite longitudinal edges of the plate 4 and formed

by bending the adjacent edge portions of the plate upwardly and inwardly, and an upright abutment lug 6 arranged at the front or inner end of the plate and formed 60 by doubling the respective part of this plate upwardly and downwardly and outwardly upon itself, as best shown in Figs. 2, 4 and 6. This base is preferably secured to the upper 65 side of the lower sash adjacent to the frame by means of screws 7, 8, passing through openings formed in the rear and front parts of the base, as shown in Fig. 2, the front screw opening being formed partly in the body of the plate 4 and partly in the folded 70 portion which forms the lug 6, so that the front screw 8 not only serves to hold the plate down upon the inner sash but also holds the lower portion 6 in its proper relative position against displacement. 75

Sliding transversely on top of the base plate 4 is a carriage or slide 9 which is guided in its movements by means of longitudinal guide flanges 10 arranged adjacent to its lower side and engaging with the 80 guideways 5 of the base. This slide or carriage may be moved transversely in a variety of ways, the means for this purpose shown in the drawings being suitable and comprising an adjusting shaft or spindle 11 arranged horizontally and transversely with reference to the sashes and having its rear or outer end provided with an external screw thread 12 which engages with an internal screw threaded opening 13 in the 85 carriage while its outer end is provided with a handle or thumb piece 14 for manipulating the same and its central part is mounted on the lug 6, so as to be capable of turning therein but held against lengthwise or axial 90 movement thereon.

The connection between this adjusting spindle and the lug 6 is preferably effected by providing the lug with an upwardly opening notch 15 in its central part into 100 which the adjusting spindle may be introduced from above, and providing this spindle with front and rear shoulders or collars 16, 17, which engage with the front and rear sides of the lug 6 and thereby confine the 105 spindle against axial movement in this lug although permitting the same to be turned freely. It follows from this construction that when the spindle 11 is turned by means of its handle or thumb piece 14, the carriage 110 9 and the parts mounted thereon will be moved horizontally and transversely on the

upper edge of the lower sash and toward and from the inner faces of the upper sash.

On the carriage are mounted a pair of gripping members which, when in their operative position, produce a grip upon the upper sash with a cam or toggle-like action, so as to prevent either of these sashes from being moved vertically relatively to each other so long as the parts remain in their operative position. In the preferred form of these gripping members they are constructed in the form of levers or toggles 18, 19, which are arranged one above the other and are pivotally connected at their front ends by means of a horizontal pivot 20 to the upper part of the carriage. For receiving these levers, the carriage is provided with a longitudinal groove 21 in its upper and rear part, and in order to permit of these levers being arranged one above the other and still obtain a uniform series, one of these levers, preferably the upper one 18, has its hub made single and arranged on the central part of the pivot pin 20, while the hub of the lower gripping lever 19 is bifurcated or made double and arranged on the pivot pin 20 so as to straddle the hub of the upper lever, as best shown in Figs. 2, 3 and 4. Normally, the gripping levers diverge rearwardly from the pivot pin 20, the lower lever being arranged below a horizontal line drawn through its pivot and the upper lever above this line. At their outer or rear ends these levers are provided with gripping jaws 22, 23, which are faced with rubber 24 or similar yielding material, which, upon engaging the inner surface of the upper sash, will obtain a firm grip thereon but will not mar the same.

When the carriage or slide is in its outer or operative position and the upper and lower gripping levers or toggles 18, 19, engage with the inner side or surface of the upper sash at points above and below a horizontal line drawn through the pivot pin 20, it will be impossible to raise or lower either one of the sashes relative to the other. This will be apparent from the fact that upon attempting a downward movement of the outer sash relative to the lower sash, the upper toggle lever 18 will resist such movement by reason of its inability to move from its upwardly inclined position to a horizontal position in line with its pivot and by reason of the fact that the sashes are held against separation in a direction transversely of the sashes in the guideways of the window frame. Upon attempting to raise the upper sash, this movement will be resisted by the locking action of the lower lever 19 which tends to swing from its downwardly-inclined position to a position horizontally in line with its pivot. The same effect will be produced upon attempt-

ing to either raise or lower the inner lower sash with reference to the upper outer sash.

When it is desired to render the sash fastener inoperative from the inside of the building so as to permit of freely opening and closing the window sashes for cleaning, ventilation or other purposes, this can be readily done by turning the adjusting screw or spindle 11 so as to withdraw the carriage a sufficient distance for this purpose, so as to disengage these levers from the upper sash. The downward movement of the lower gripping lever 19 is limited by engagement of the upper side of the base plate 4, so that the same is always in position to properly reengage the inner side of the upper sash when the carriage is moved outwardly into its operative position. Inasmuch however, as the upper gripping lever 18 would, in the absence of any provision to prevent it, drop from its upwardly inclined position into a nearly horizontal position when free, means are provided for yieldingly holding the same in its elevated inclined position while the carriage is moved into its operative position. For this purpose the carriage is provided in the bottom part of its notch with a detent spring 25 which has an upwardly curved salient portion adapted to be engaged by a detent nose 26 on the underside of the upper lever and the latter is also provided with a shifting finger 27 projecting inwardly therefrom. When therefore it is desired to render the sash fastener inoperative and leave the same in such condition that it can be promptly rendered operative, the attendant first depresses the finger piece 27 so that the nose 26 of the upper gripping lever 18 springs from the inner side of the salient part of the detent spring 25 to the outer side thereof, whereby this lever will be yieldingly held in this position by this spring while the carriage 9 is withdrawn from the upper sash into its inoperative position. When returning the sash fastener to its operative position, the carriage 9 is first moved outwardly by means of its adjusting screw until the jaw of the lower lever 19 is in proper engagement with the upper sash and then the shifting finger 27 is raised for turning the upper lever 18 downwardly until its jaw also engages with the inner side of the upper sash, during which movement of this lever its nose 26 rides over the salient part of the detent spring 25 from the front to the rear side thereof, into the position shown in Fig. 2, thereby returning the parts to their normal operative position.

Taken as a whole, the sash fastener is comparatively simple in construction considering the various functions which it performs; it can be applied to most windows without any fitting or alteration of parts,

and it can be very easily and conveniently operated for either lowering or releasing the windows and owing to its compactness, the same does not detract from the appearance 5 of the window.

I claim as my invention:

1. A sash fastener adapted to be interposed between two relatively movable members of a window, comprising a base plate 10 adapted to be mounted on one of said window members, a carriage slidable on said base plate, a pair of gripping levers or toggles pivoted at one of their corresponding ends on said carriage and adapted to engage 15 their opposite ends with the other window member, one of said levers engaging with said last mentioned window member on one side of the axes of said levers and the other gripping lever engaging with said last 20 mentioned window member on the opposite side of the axes of said levers and slidable on said base plate.

2. A sash fastener adapted to be interposed between two relatively movable window members, comprising a base adapted to be secured to one of said window members and provided with a transverse guideway, a carriage slidable in said guideway, upper and lower gripping levers pivoted at their 25 inner

ends on said carriage and adapted to engage 30 their outer ends with the other window member on opposite sides of the axis of the pivotal connection between said levers and said carriage, means for adjusting said carriage on said base, said lower lever sliding 35 on said base, and yielding means for holding said upper lever in its elevated position.

3. A sash fastener adapted to be interposed between two relatively movable window members, comprising a base adapted to be secured to one of said window members and provided with a transverse guideway, a carriage slidable in said guideway, upper and lower gripping levers pivoted at their 40 inner ends on said carriage and adapted to engage 45 their outer ends with the other window member on opposite sides of the axis of the pivotal connection between said levers and said carriage, said lower lever sliding on said base, and said upper lever being provided with a nose adjacent to its fulcrum, and a spring mounted on said carriage and having a salient portion one side or the other of which is adapted to be engaged 50 by the nose of said upper lever.

ALBIN H. HUTCHINGS.
